CONVERTIBLE COUCH

Ewald A. Kamp, 1720 Merchandise Mart, Chicago, Ill.

Filed Mar. 24, 1961, Ser. No. 64,464

Term of patent 14 years

(Cl. D5—4)

*Fig. 4.Fig. 5.*FIG. 1 is a front perspective view of a convertible couch showing my design;

FIG. 2 is a front perspective view thereof in open position;

FIG. 3 is an elevational view of one side of the couch of my design;

FIG. 4 is a rear perspective view of the couch of my design; and

FIG. 5 is an elevational view of the opposite side of the couch of my design.

I claim:

The ornamental design for a convertible couch, substantially as shown.
